UNITED STATES PATENT OFFICE.

EDWARD F. LANGER, OF KAMPSVILLE, ILLINOIS.

ALL-METAL SCREEN-CARRYING WINDOW FRAME.

Application filed January 21, 1927. Serial No. 162,505.

My present invention pertains to screen carrying window frames, and contemplates the provision of such a frame made entirely of metal and one that is readily adjustable in width and length, and is adapted to be shipped in disassembled shape, and to be readily assembled and set up for use and this without the employment of skilled labor and without the assistance of any tool with the exception of an ordinary screw driver.

Other objects and practical advantages of the invention will be fully understood from the following description and claims when the same are read in connection with the drawings, accompanying and forming part of this specification, in which:—

Figure 1 is a face view showing the all metal screen carrying window frame constituting the preferred embodiment of my invention and as the same appears when ready for use or in use.

Figure 2 is an enlarged fragmentary cross section taken on the plane indicated by the line 2—2 of Figure 1, looking upwardly.

Figure 3 is an enlarged fragmentary vertical section taken on the plane indicated by the line 3—3 of Figure 1.

Figure 4 is an enlarged broken face view showing a portion of the frame body.

Figure 5 is a face view of one of the corner members embraced in said frame body.

Figure 6 is a view of one of the sections comprised in said corner member.

Figure 7 is an end elevation of said section.

Figure 8 is a view showing the comparatively wide edge of said section.

Figure 9 comprises disconnected views of the members of the middle brace of my improvement.

Figure 10 is an enlarged detail view illustrative of the manner in which the wire screen is fastened to the frame body.

Figure 11 is a broken perspective showing a portion of one of the ornamental covering bars of the frame, said bars being denominated covering bars inasmuch as they hide from view the fasteners through the medium of which the fire screen is fastened to the frame body, and at the same time enhance the finished appearance of the window frame.

Figure 12 is a detail perspective on an enlarged scale showing one of the clips through the medium of which the covering bars are held in working position on the space of the frame body.

Figures 13, 14, and 15 are broken views of

one of the sections of the screen body which are interposed between the aforementioned corner members.

Figure 16 is an elevation showing the outer end of one of the sections comprised in the middle frame of the frame body.

Similar numerals of reference designate corresponding parts in all the views of the drawings.

For the sake of clearness and convenience I will first describe the body of my novel all-metal frame. The said body of the frame comprises four corner members such as the member 1 shown in Figure 5, four interposed sections, such as the section 2 in Figures 13, 14, and 15, and a middle brace 3, said brace being shown incorporated in the body in Figure 4, and being shown in detail in Figures 9 and 16. It will also be noticed that the middle brace 3 is illustrated in Figures 1 and 3.

Each corner member 1 comprises sections 2^x at right angles to each other, and it will be noted that each section 2^x is of sheet metal 80 and has an outer hollow portion 4 of triangular form and inner portions 5 arranged side by side and close together. The contiguous ends of the enlarged portions 4 of the sections 2^x at right angles to each other are shaped as shown to form a miter joint 6, and the inner portion 5 of one of the sections 2^x is arranged in lapped relation to the corresponding portion of the section at right angles and is connected to the latter section through the medium of stove bolts 7. It will also be noted that each of the sections 2^x is provided in its portions 5 with apertures 8 for the reception of the shank of the wire screen fasteners 9 hereinafter described in detail.

Each of the four interposed sections 2 is of a single piece of sheet metal, and is provided with enlarged portions or heads 10, of triangular cross section, the ends of which are reduced as indicated by 11, and closely arranged side by side portions 12, best shown in Figure 15. It will also be noted that the side by side and closely arranged portions 12 of the sections 2 are longitudinally slotted and designated by 13 and best shown in Figure 14. The end portions of the intermediate sections or interposed sections 2 are telescopically arranged in portions of the arms or sections of the corner members 1, and are connected to the same through the medium of stove bolts 14 which pass through the before mentioned slots 13. From this it

follows that the ends of the frame as well as the sides of the frame or frame body are adapted to be increased or diminished in length as occasion demands.

5 As clearly shown in Figures 4 and 14, the closely arranged side by side portions 12 of the interposed sections 2 are apertured as indicated by 15 for the passage of the shanks of fasteners such as 9. The middle brace 3 of the 10 frame body is made up of two sections 16 of sheet metal, such as best shown in Figures 4, 9 and 3. It will be noted from Figure 9 in comparison with Figure 16 that each section 16 is provided with a channel portion 17, 15 and with a flat edge 18 outwardly beyond the channel portion and of a greater width than the said channel portion. It will also be noted that each section 16 is apertured at 19 and longitudinally slotted at 20 and 21, the slots 20 of the two sections 16 being for the passage of stove bolts 22 by which the sections 16 are connected to the side by side portions 12 of side sections 2, and the slots 21 in the inner end portions of the sections 16 which portions 25 are designed to be arranged in lapped relation as shown in Figure 4, being adapted to receive a connecting stove bolt such as designated by 23 in Figure 4. The outer ends of the sections 16 are designed to abut against 30 the heads or enlargements 10 of the side sections 2 as is brought out in Figure 4 of the drawings.

It is believed that from the foregoing, the 35 body of my novel frame will be readily comprehensible; and it will be appreciated that the said body is easy to assemble and this without the employment of skilled labor or any tool other than an ordinary screw driver. It will be appreciated that the said frame 40 body is susceptible of being easily manufactured, and from the standpoint of a dealer the said body is possessed of several practical advantages. For instance, the corner members shown in Figure 5 fits frames of all sizes, the 45 corner members designated by 1 always remaining the same. From this it follows that one kind of corner member 1 only need be stocked. The interposed sections 2 may be, and preferably are sockets in assorted length 50 and are interchangeable for use at the side or at the ends of the frame. It will further be appreciated that the frame body constructed as described lends itself to ready adjustment of the screen frame as a whole to windows of different sizes.

The wire screen of my improvement is 55 designated by 24 and is lapped over the sections 16 of the middle brace 3, and over the inner closely arranged portions 12 of the interposed sections 2 after the manner shown in Figures 3 and 2, respectively.

The fasteners 9 may be, and preferably are 60 of the ordinary well known bendable type, the said fasteners having heads to be arranged 65 at one side of the wire screen 24, and also hav-

ing side by side prongs constituting shanks which are adapted to be passed through interstices of the wire screen and through apertures of the portions of the frame body, and the said prongs being adapted to be bent with 70 the fingers in opposite directions at the opposite sides of the body portions relative to the wire screen 24. When applied and arranged as stated, the fasteners 9 will manifestly strongly hold the wire screen 24 to and on 75 the frame body.

For the purpose of hiding and covering the fasteners 9 and the edges of the wire screen 24 and also for the purpose of generally enhancing the finished appearance of the window frame I employ covering bars 25, preferably of sheet metal. The said covering bars 25 are preferably shaped in cross section as shown in Figure 2, and in Figure 3, and at the sides of the frame and also at the ends thereof as well as on the middle brace 3, two covering bars 25 may be and preferably are arranged, the contiguous portions of the said bars being lapped. From this it follows that the covering portions of my improvement may be increased or diminished in length when the frame is adjusted to increase the frame body in width or in length.

For the purpose of detachably securing the covering bars 25 on the adjacent portions of the frame body I provide clips 26, the said clips 26 being bifurcated at 27 for the passage of the shank of stove bolts 28 by which the clips are connected to the frame body, and the said clips also having portions 29 shaped to snugly fit and rest over the angular shaped portions of the covering bars 25. By virtue of this provision it will be understood that each of the covering bars 25 will be strongly though detachably secured in working position so as to cover the fasteners 9 and the edges of the wire screen 24 and then to the finished appearance of the frame as a whole as before stated.

By reference to Figure 1 it will be understood that the outer ends of the side covering bars 25 are mitered to lap over the end covering bars with the result that the finished appearance of the structure is increased. It will also be noted in this connection that the covering bars 25 complementary to the middle brace 3 are mitered to fit the angular portions of the side covering bars 25, for the purpose indicated.

When deemed expedient the body of my novel screen carrying window frame may be provided with apertured hangers 30 through the medium of which the screen carrying frame may be connected with and suspended on a window frame which is to be guarded by the wire screen 24.

It will be appreciated from the foregoing that notwithstanding the all-metal character and the fire proof qualities of my novel screen carrying window frame, the said frame as a 130

whole is, by virtue of its construction, light in weight.

I have entered into a detailed description of the construction and relative arrangement 5 of parts embraced in the present and preferred embodiment of my invention in order to impart a full, clear, and exact understanding of said embodiment. I do not desire, however, to be understood as limiting myself 10 to the precise structure disclosed, my invention being defined by my appended claims within the scope of which modifications may be made without departure from my invention.

15 Having thus described the invention, what I claim as new and desire to secure by Letters Patent is:—

1. In combination, a body bar, means for connecting a wire screen to the said body bar, 20 a bar arranged over and hiding the means for connecting a wire screen to the body bar, means for holding the second named bar to and on the body bar; the said means for holding the second named bar to and on the 25 body bar being in the form of clips resting over the second named bar and directly attached to the body bar at points alongside and outwardly beyond the second named bar.

2. In combination, a body bar, means for 30 connecting a wire screen to the body bar, a bar arranged over and hiding said means for connecting the wire screen to the body bar, and means for holding the second named bar to and on the body bar; the said body bar 35 having an outer enlarged hollow portion, of angular cross section, an interlapped portion and the second named bar being of angular cross section and spaced inwardly from said hollow portion, and the said means for holding the second named bar to and on the body bar being in the form of angular clips directly attached to the body bar outwardly beyond and alongside the second named bar and arranged inwardly of said hollow portion and 45 straddling the second named bar.

3. A body comprising corner members, each 50 with outer hollow portions and with inner portions arranged side by side and against each other, and interposed end and side sections having outer hollow portions and inner portions side by side and against each other and further having reduced ends socketed

in and adjustably connected to the corner members.

4. In combination, a body having apertures, fasteners adapted to be connected to a wire screen and to extend through apertures of the body and being secured at the rear side of the body, a bar having an angular portion arranged over and completely covering 55 said fasteners, and clips having angular portions straddling the angular bars and also having portions connected to the body at points alongside of and outwardly beyond said bar.

5. In combination, corner members having outer hollow portions and inner portions, the latter arranged side by side and together, interposed side and end sections having hollow 60 outer portions and inner closely arranged portions and further having reduced end portions and longitudinal slots therein, and bolts extending through said slots and adjustably connecting the interposed end and side sections to the corner members.

6. The combination of corner members having hollow outer portions and inner portions arranged side by side and together, interposed side and end sections having hollow outer portions and also having inner 70 portions arranged side by side and against each other and further having reduced end portions and longitudinal slots therein, and bolts extending through said slots and adjustably connecting the interposed end and side sections to the corner members; the inner portions of the corner members and interposed sections being apertured to facilitate the connection of the wire screen or the 75 like to the same.

7. In combination, a body bar having apertures, means adapted to extend through said apertures to connect a wire screen or the like to the body, means adapted to be arranged over a wire screen or the like and the said 80 connecting means and completely hiding said connecting means and contributing to the finished appearance of the structure, and means connected directly to the body bar outwardly beyond the covering means and 85 holding said covering means on the body bar.

In testimony whereof I affix my signature.

EDWARD F. LANGER.
